UNITED STATES PATENT OFFICE

GAETANO PRESTIGIACOMO, OF NEW YORK, N. Y.

DESIGN FOR AN AUTOMOBILE BODY

Application filed June 23, 1931. Serial No. 40,308. Term of patent 14 years.

To all whom it may concern:

Be it known that I, G. PRESTIGIACOMO, a citizen of the United States, residing in New York, in the county of Bronx and State of New York, have invented a new, original, and ornamental Design for the Automobile Body, of which the following is a specification, reference being had to the accompanying drawings, forming part thereof in which,

I claim:

The ornamental design for an automobile body, as shown.

GAETANO PRESTIGIACOMO.
